UNITED STATES PATENT OFFICE.

JAMES M. MUNGIVEN, OF BROOKLYN, NEW YORK.

PAINT-CAN PRESS.

SPECIFICATION forming part of Letters Patent No. 356,205, dated January 18, 1887.

Application filed July 26, 1886. Serial No. 209,099. (No model.)

To all whom it may concern:

Be it known that I, JAMES M. MUNGIVEN, of Brooklyn, in the county of Kings and State of New York, have invented an Improvement 5 in Paint-Can Presses, of which the following is a specification.

Paint-can presses have been made in which the paint-can is received on a table or base and a plunger fitting into the can is pressed 10 down by a rack and pinion. In this kind of press there is nothing to hold up the plunger while the can is being put into place, and the weight of the plunger is constantly resting upon the paint and tending to force it up between the can and the plunger.

My improvement is made for overcoming these objections and for holding the plunger in any desired position, either elevated or pressed upon the paint.

20 In the drawings, Figure 1 is a front elevation of the press. Fig. 2 is a side elevation, partially in section, and Fig. 3 is a plan view.

The shelf or base *a* projects as a ring from the vertical standard *b*, and it is supported by 25 brackets *cc* below the ring and diverging from the standard. This standard *b* is a hollow bar that is adapted to be screwed to a wall partition or stud, and at the upper end there is an arm, *e*, that projects outwardly and terminates 30 as a hollow head, *f*, with a socket, *g*.

The vertical slide-bar *h* is V-shaped sectionally, and it slides in a corresponding bearing, *i*, in the head, and the face is guided by the cross-bar *k*, and in the face of this bar *h* 35 are teeth.

In the hollow head *f* is the scroll-pinion *l*, the arbor of which passes through the socket *g* and is provided with a crank-handle, *m*, and the inner end of the arbor passes into a square 40 recess in the center of the scroll-pinion, and the screw *n* passes through the arbor and

screws into the center of the pinion to connect the parts together.

The face of the scroll-pinion is conical, and it has one, two, or more scroll-threads upon 45 it, fitting the teeth upon the face of the slide-bar *h*; hence this scroll-pinion will raise or force down the slide-bar *h* when the pinion is rotated, and it will keep the parts in any position to which they may be moved. 50

The slide-bar *h* is to be passed up through the ring-shelf *a* after the scroll-pinion has been put into place, and then the plunger *r* is screwed or fastened to its lower end. This plunger *r* is to be of a size to pass into the 55 paint-can, and acts to press out the contents through a tube or cock when the scroll-pinion is turned to force down the slide-bar and plunger. The can rests upon the ring-shelf *a*, and as cans adapted to this press are well 60 known I have not represented or described the same.

The disk or plunger *r* can be disconnected by unscrewing it from the slide-bar and a different-sized disk substituted. 65

I claim as my invention—

The combination, in a paint-can press, with the toothed slide-bar and the hollow head, of the scroll-pinion within the head and having a central recess, the crank and the arbor for 70 the same passing through a socket on the head, the end of the arbor being polygonal to fit the recess in the pinion, and a screw passing through the arbor and into the scroll-pinion to connect the parts, substantially as set 75 forth.

Signed by me this 19th day of July, 1886.

JAMES M. MUNGIVEN.
